UNITED STATES PATENT OFFICE.

WILLIAM P. FRANK, OF CHICAGO, ILLINOIS.

TUBE-BENDING MACHINE.

1,225,426.

Specification of Letters Patent.

Patented May 8, 1917.

Application filed December 18, 1915. Serial No. 67,606.

To all whom it may concern:

Be it known that I, WILLIAM P. FRANK, a citizen of the United States, and a resident of the city of Chicago, county of Cook, 5 and State of Illinois, have invented certain new and useful Improvements in Tube-Bending Machines, of which the following is a specification.

My invention relates to improvements in 10 tube bending machines, and has for its object the provision of an improved construction of this character which is capable of bending tubes without buckling or distorting the same.

15 The invention consists in the combinations and arrangements of parts hereinafter described and claimed.

The invention will be best understood by reference to the accompanying drawings 20 forming a part of this specification, and in which,

Figure 1 is a plan view of a construction embodying my invention,

Fig. 2, a section taken on line 2—2 of 25 Fig. 1,

Fig. 3, a horizontal section of the construction, and

Fig. 4, a section taken on line 4—4 of 30 Fig. 3.

The preferred form of construction, as 35 illustrated in the drawings comprises a base plate 5 which may be secured in a vise or mounted in any suitable or desired manner.

A rotatable head 6 is mounted on said base, 40 said head being provided with a spindle 7 rotating freely in said base. Head 6 is provided with an annular groove 8 adapted to receive the corresponding portion of a tube 9 to be bent. The head 6 is provided with

registering notches 10 at one side thereof 45 and a pin 11 is insertible through said notches and also through a perforation formed in the corresponding end of the tube 9. A die member 12 is arranged to encom-

pass substantially one-half of the head 6 and 50 is provided with a groove 13 corresponding with groove 8 and coöperating therewith to form a recess and guide of a size to just accommodate tube 9. An extension 14 is pro-

vided on die member 12 extending a short 55 distance substantially tangentially to the head 6 and is provided with a groove 15 constituting a tangential extension of groove 13, as indicated. A wedge member 16 is ar-

ranged between die member 12 and an abut- 55 ment 17 on base plate 5 and serves as a

means for forcing die member 12 into co-operative relation with head 6 and holding it there.

A plug 18 of a size to fit nicely within 60 tube 9 is mounted on one end of a threaded stem 19 resting loosely in a slot in a bracket 20 on base plate 5. The stem 19 is provided with lock nuts 21 by means of which its position may be adjusted longitudinally and 65 the bracket 20 is so situated that the plug 18 may be positioned, as indicated in Fig. 3, substantially tangential to the head 6 and with its end terminating substantially at the tangential point. An operating handle or 70 lever 22 is provided with pins 23 adapted to fit within corresponding openings in the top of head 6 to serve as a means for rotating said head.

In use the parts are arranged as indicated 75 in Fig. 1 with the plug 18 arranged within the tube 9 and pin 11 traversing the perforation in the end of said tube. Then head 6 is turned by means of lever 22 to draw the tube end around through the groove 13 in die member 12. This will cause bending of 80 the tube into semi-circular form without buckling or materially distorting the same. The plug 18 resting within the tube serves to prevent inward buckling of the metal at 85 the tangential point which is the point where the bending takes place, and the walls of the grooves 13 and 8 prevent outward distortions of said tube. By this construction, I find that tubes may be quickly and accurately bent by a single manipulation or operation without material distortion thereof.

While I have illustrated and described 90 the preferred form of construction for carrying my invention into effect, this is capable of variation and modification without departing from the spirit of the invention. I, therefore, do not wish to be limited to the precise details of construction set forth, but 95 desire to avail myself of such variations and modifications as come within the scope of the appended claims.

Having described my invention what I 100 claim as new and desire to secure by Letters Patent is:

1. A tube bending machine comprising a 105 rotatable element provided with means for engaging a tube; a plug insertible in a tube engaged by said element; and a grooved die, partially encircling and coöperating with 110 said element, substantially as described.

2. A tube bending machine comprising a

grooved rotatable element provided with means for engaging a tube; a plug insertible in a tube engaged by said element; and a grooved die partially encircling and co-
5 operating with said element, substantially as described.

3. A tube bending machine comprising a base; a grooved head rotatably mounted in said base; a grooved die partially encircling
10 and coöperating with said head; a wedge for forcing said die into coöperating relation with said head; a threaded stem anchored

on said base substantially tangential to said head; and a plug on said stem positioned substantially at said tangent point and in-
15 sertible in a tube arranged in said grooves, substantially as described.

In testimony whereof I have signed my name to this specification in the presence of two subscribing witnesses.

WILLIAM P. FRANK.
